UNITED STATES PATENT OFFICE.

ELMER E. LANE, OF BEVERLY, MASSACHUSETTS, ASSIGNOR TO UNITED SHOE MACHINERY COMPANY, OF PATERSON, NEW JERSEY, A CORPORATION OF NEW JERSEY.

BLANK-FITTING MACHINE.

1,195,823.

Specification of Letters Patent. Patented Aug. 22, 1916.

Application filed December 17, 1915. Serial No. 67,420.

To all whom it may concern:

Be it known that I, ELMER E. LANE, a citizen of the United States, residing at Beverly, in the county of Essex and State 5 of Massachusetts, have invented certain new and useful Improvements in Blank-Fitting Machines; and I do hereby declare the following to be a full, clear, and exact description of the invention, such as will enable 10 others skilled in the art to which it appertains to make and use the same.

This invention relates to blank fitting machines and more particularly, to a blank feeding mechanism for blank fitting 15 machines.

Machines for skiving box toe and counter blanks generally employ an automatic feeding mechanism which feeds blanks from a stack supported in a magazine. The blanks 20 in the magazine are acted upon by a follower which holds them down in position to be taken one at a time by the feeding mechanism. To prevent more than one blank at a time to be fed to the skiving devices, the space between the bottom of the 25 front wall of the magazine and the table on which the blanks are supported must be but slightly wider than the thickness of one blank. Blanks of certain kinds of material 30 are quite stiff and often curl up or become warped so that they cannot be positioned to go under the front wall of the magazine or be engaged by the feeding mechanism to be properly fed to the skiving devices.

35 The primary object of the present invention is to provide a feeding mechanism for a skiving or other blank fitting machine by which warped or curled blanks may be properly fed to the blank treating devices.

40 In accordance with this object, one feature of the invention contemplates the provision in a blank fitting machine having blank feeding and positioning rolls, a reciprocatory feeding means for presenting blanks to 45 the rolls in timed relation to their operation, a table for supporting the blanks, and a gate above the table for holding the blanks down upon the table, of yieldingly mounted plungers behind the gate which will extend 50 across the blank to flatten it on the table in a proper position to be engaged by the feeding means. In the preferred form of the invention the blanks are held down during the feeding operation by a spring pressed 55 gate, and the yieldingly mounted plungers

for flattening the blanks are mounted upon the gate and tend to force the blank under the gate as it is being fed. The plungers have sufficient drag on the blank to hold it back so that it will be adjusted longitudinally by the feeding means and properly presented to the rolls.

The invention also includes certain further features of construction and combinations of parts which are hereinafter described and set forth in the claims.

The several features of the invention are illustrated in the accompanying drawings, in which—

Figure 1 is a plan view partly in section, 70 of a cavity roll skiving machine embodying the preferred form of the invention; Fig. 2 is a view in vertical section of the machine shown in Fig. 1, illustrating the skiving devices and feeding mechanism; and Fig. 3 75 is a detail view of the improved feeding mechanism.

The machine illustrated in the drawings is substantially the same in the construction, arrangement and mode of operation of its various parts as the machine shown in the patent to Scott No. 969,987, dated September 13, 1910. This machine is provided with a cavity or die roll 10, a feed or pressure roll 12, and a fixed skiving knife 14 which has its cutting edge extending close to the line of contact of the die and pressure rolls with the blank. The blanks are supported upon a table 16 and fed forward to the bite of the die and pressure rolls by means of a slide 18. The slide 18 makes a complete reciprocation during each revolution of the die and pressure rolls and is operated in timed relation thereto so that a blank presented by the slide will register with the cavity 20 in the roll 10. The parts above referred to are substantially the same as those shown in the patent above referred to.

Counter and box toe blanks of certain kinds of material are very stiff and often curl up and become warped. These blanks cannot be arranged in a stack and automatically fed from a magazine such as is shown in the patent to Scott above referred to, because the follower which holds the blanks down on the table cannot be regulated to give the proper pressure to straighten the blanks so that they can be properly fed by the feed slide. If the follower is regulated to give sufficient pressure 100

to flatten the blanks on the table, they are clamped so tight that the feed slide will not properly feed them. To adapt this type of machine for skiving warped or curled blanks, the follower is done away with and the machine is run at a speed which permits the blanks to be placed by hand one at a time in position to be acted upon by the feed slide.

- 10 The machine shown in the drawings is provided with the usual movable gate 22 which is pressed toward the table by springs 23 mounted at each end of the gate. This gate assists in holding a blank against the 15 table while it is being presented to the die and pressure rolls. The bottom of the gate is cut away at 24 to aid in starting the blank in under the gate and also to allow the feed slide to pass under the gate. To insure that 20 the blank shall pass under the gate, a series of plungers 26 for guiding the blank are mounted in bearings 28 which are attached to the front of the gate. These plungers are pressed toward the table 16 by means of stiff 25 springs 30, the pressure of which may be adjusted by means of screws 32. The plungers 26 also serve to flatten a blank on the table sufficiently so that it will be engaged and moved forward by the feed slide 18. To 30 this end guide fingers 34 are formed on the plungers which project rearwardly and upwardly from the gate. The fingers extend out far enough from the gate so that when a warped blank is pushed thereunder, it will 35 be flattened on the table in position to be engaged by the feed slide.

The feed slide usually employed in this type of machine is generally slightly thinner than the thickness of the blank. To facilitate the feeding of warped or curled blanks, the feed slide of the machine illustrated is built up with a plate 36 to give a comparatively wide face for contact with the blanks. The effective pressing faces of 45 the plunger fingers 34 extend far enough across a blank to hold it down sufficiently so that the pushing face of the slide will engage the blank to feed it in timed relation to the movement of the rolls. The pressure of 50 the springs 30 causes the plungers 26 to drag on the blank and hold it back against the pushing face of the slide 18 and plate 36 so that it will be in proper position to be presented to the feed rolls. The feed slide 55 18 is slotted at 38 to permit the slide to pass the plungers when presenting blanks to the feed rolls, and the cut out portion 24 in the gate 22 allows the feed plate 36 to pass under the gate.

- 60 The forward edge of the feed slide acts as a gage to properly longitudinally position the blanks so that they may register with the cavity of the die roll, and a gage 40 is used to transversely position the blanks. 65 The gage 40 is mounted on a carrier 42

which is carried by the usual guard plate 44 that covers the feed slide. The carrier 42 may be adjusted transversely of the machine table by means of a slot 46 in the carrier and a bolt 48 in the guard plate. The gage 70 75 40 is pivotally mounted on the carrier 42 and is normally held against the table 16 by means of a leaf spring 50 which is attached to the carrier 42 and bears against a pin 52 on the gage 40. This pivotal mounting of the gage permits it to rise and fall to allow the feed slide to pass under it when feeding a blank.

To better adapt the machine for hand feed, a guide plate 54 is attached to the front 80 85 end of the guard plate 44. The upper face of the guide plate 54 is rounded and inclined toward the table 16 and is directly opposite the upwardly inclined fingers 34 on the plungers. With this construction a slot is 85 90 formed between the fingers 34 and the face of the guide plate, into which the blanks may be placed to flatten them on the table to be engaged by the feed slide. The guard plate 44 with the guide 54 may be adjusted relatively to the gate 22 so that the forward edge of the blank will be clamped under the fingers 34 when the rear edge of the blank passes the guide 54 to rest on the table. 95

The operation of the machine is as follows: The blanks to be skived are placed in a pile upon the guard plate 44 and the machine set in operation. The feed slide reciprocates back and forth, and during the backward stroke of the feed slide the operator pushes a blank into the slot between the fingers 34 and guide plate 54 until the end of the blank passes the guide plate. The plungers press the blank toward the table, and when the slide has passed under the 100 105 guide plate 54 and guard plate 44, the blank is forced down upon the table by the fingers 34. In placing the blank into the slot, the operator holds one edge against the gage 40 to transversely position the blank, and on the forward stroke of the feed slide if the blank is not in proper longitudinal alignment to engage the front edge of the slide 18, one end or the other of the blank will be pushed forward until it is in proper alignment. While the blank is being placed in proper longitudinal alignment, however, the fingers 34 clamp the blank against the table with sufficient pressure to hold the edge of the blank in contact with the gage 40, so 110 115 that the transverse position of the blank will not be altered. It is not important that the plungers completely flatten the blank, because the feed slide is built up to form a high enough edge to engage a blank which is slightly warped. The upwardly inclined arrangement of the fingers, however, insure 120 125 that the front edge of the blank will be pressed hard enough against the table so that it will pass under the gate as it is be-

ing advanced to the feed rolls. If the blank is not flat, the gate will, in turn, assist the plungers in holding it down upon the table, because the portions of the gate, extending 5 beyond the slot 24 into which the plate 36 passes, will engage the blank as it is advanced to the feed rolls.

In the preferred form of the invention 10 two plungers are used for holding the blank upon the feed table, but it is to be understood that the number and location of such plungers depend upon the length and kind of blanks to be skived.

While the invention has been illustrated 15 and described as embodied in a skiving machine, it is obvious that it could be used in most any type of blank fitting machine which has a hand feed for feeding blanks one at a time in a definite relation to blank treating 20 devices.

In the specification and claims, the terms "forward", "front", "rearwardly", and "behind", have been used to denote the relative 25 position of the parts in the machine, and this position is determined with reference to the direction of the feeding of the blanks.

Having thus described my invention, what is claimed as new, is:—

1. A blank fitting machine having, in 30 combination, blank feeding and positioning rolls, a reciprocatory feeding means for presenting a blank to the rolls in timed relation to their operation, a table for supporting a blank, a gate above the table behind the 35 rolls, a guide plate mounted above the table, and yieldingly mounted plungers behind the gate having fingers thereon which extend far enough toward the guide plate to flatten a blank on the table between the gate 40 and guide plate.

2. A blank fitting machine having, in 45 combination, blank feeding and positioning rolls, a reciprocatory feeding means for presenting a blank to the rolls in timed relation to their operation, a table for supporting a blank, a gate above the table behind the rolls, and yieldingly mounted plungers behind the gate which extend across the blank to flatten it on the table sufficiently to 50 be engaged by the feeding means.

3. A blank fitting machine having, in 55 combination, blank feeding and positioning rolls, a reciprocatory feeding means for presenting a blank to the rolls in timed relation to their operation, a table for supporting the blank, a gate above the table behind the rolls, a guide plate mounted above the table behind the gate, and yieldingly mounted plungers between the gate and guide 60 plate having fingers which extend rear-

wardly and upwardly toward the guide plate to form a slot with the guide plate into which the blank may be forced by hand to flatten it on the table in the path of the feeding means.

65

4. A blank fitting machine having, in combination, blank feeding and positioning rolls, a reciprocatory feeding means for presenting a blank to the rolls in timed relation to their operation, a table for supporting the blank, a yieldingly mounted gate behind the rolls for holding the blank upon the table, and plungers mounted on the gate having rearwardly and upwardly extending fingers for forcing the blank under the gate 70 as it is fed to the rolls.

5. A blank fitting machine having, in combination, blank feeding and positioning rolls, a reciprocatory feed slide for presenting a blank to the rolls in timed relation to 80 their operation, said slide having a pushing face of greater height than the thickness of the blank, a guide plate over the feed slide, a table for supporting a blank, and spring pressed plungers having fingers extending in close proximity to the end of the 85 guide plate for pressing the blank against the table in the path of the pushing edge of the feed slide.

6. A blank fitting machine having, in 90 combination, blank feeding and positioning rolls, a reciprocatory feeding means for presenting a blank to the rolls in timed relation to their operation, a table for supporting a blank, a guide plate mounted above the 95 feeding means, a gage on the table for determining the transverse position of the blank, and spring pressed plungers mounted above the table to clamp the blank on the table and maintain the transverse position of the 100 blank while the feeding means adjust it longitudinally to be properly positioned in the rolls.

7. A blank fitting machine having, in 105 combination, a blank skiving mechanism, blank feeding and positioning rolls, a reciprocatory feeding means for presenting a blank to the rolls in timed relation to their operation, a table for supporting the blank, a guide plate mounted above the feeding 110 means having a face inclined toward the table, a series of yieldable plungers behind the rolls having rearwardly and upwardly extending fingers mounted opposite the inclined face of the guide plate to form a slot 115 into which the blank may be forced by hand to hold the blank upon the table, and a gage on the guide plate for positioning the blank.

ELMER E. LANE.
